UNITED STATES PATENT OFFICE.

JACOB KILCHER, OF MOUNT PLEASANT, IOWA.

CELLAR-WINDOW VENTILATOR AND GUARD.

Application filed September 27, 1923. Serial No. 665,203.

To all whom it may concern:

Be it known that I, JACOB KILCHER, a citizen of the United States, residing at Mount Pleasant, in the county of Henry and State of Iowa, have invented certain new and useful Improvements in a Cellar-Window Ventilator and Guard; and I do declare the following to be a full, clear, and exact description of the invention, such as 10 will enable others skilled in the art to which it appertains to make and use the same.

My invention relates to guards and ventilators for windows and more particularly to one which is designed primarily for use in 15 connection with inwardly swinging cellar windows, the invention being adapted to guard the opening when the window is swung into said guard, to an open position, thus preventing the entrance of rats or other 20 small animals, trash, thieves, etc.

One object of the invention is to provide a simply constructed and inexpensive guard of the class defined, yet one which will be 25 very desirable.

Another object is to provide a guard which is movable away from the window frame and bodily carries the hinged window, this arrangement being very desirable 30 when it is necessary to have the window opening exposed, for instance when placing coal in the cellar.

With the foregoing in view, the invention resides in the novel subject matter herein-after described and claimed, the description 35 being supplemented by the accompanying drawings.

Figure 1 is an inner side elevation of the guard applied to a window.

Figure 2 is an end elevation.

Figure 3 is a vertical sectional view on line 3-3 of Fig. 1, showing the window closed.

Figure 4 is a duplicate of Fig. 3, with the exception that it shows the window swung 45 into the guard.

Figure 5 is a horizontal sectional view as indicated by line 5-5 of Fig. 1.

In constructing the preferred form of my invention, I make use of a vertically disposed rectangular frame 1, formed of metal and adapted to be connected with the frame 2 of an inwardly swinging window 3, the frame 1 being adapted to extend around the four sides of the frame 2, as shown. Se- 50 cured at their ends to the top and bottom bars of the frame 1, are a number of sub-

stantially C-shaped bars 4, whose body portions preferably incline as shown. These body portions are preferably secured to a horizontal bar 5 whose ends 6 are turned laterally and secured to the vertical ends of the frame 1, and vertical bars 7 having lateral ends 8 are secured to the endmost bars 4. 60

Extending over the frame structure described, and forming therewith a guard cage, is a covering 9 of woven wire, whose edges are secured to the frame 1, this cage being of such shape that the window 3 may be swung inwardly into it, as disclosed in Fig. 4. In the preferred form of construction, the window hinges 10 connect the window directly with the top bar of the frame 1 and the latter is detachably connected with the window frame 2, permitting the cage and the window to be bodily moved 70 from the frame, when desired. One of the vertical ends of the frame 1 is hinged at 11 to the window frame 2, and a removable pintle rod 12 is provided for the hinges, said rod being normally held against removal 75 by a pivoted latch 13. When this latch is released, however, the rod 12 may be withdrawn from the hinge knuckles and thus the adjacent end of the frame 1 and associated parts, are disconnected from the window 80 frame. At the opposite end of the cage, I have shown a pair of securing bars 14 positioned horizontally, the outer ends of said bars having hooks 15 which take over one of the endmost bars 4, while the inner ends 90 of the bars 14 are provided with lateral feet 16 detachably secured by bolts and wing nuts 17, or connected by other preferred means to the frame 2. When desired, the bars 14 may be released and the 95 entire guard cage and the window 3, may be horizontally swung away from the window frame 2, but when these parts are to be entirely disconnected from said frame 2, the latch 13 is released and the pintle rod 100 12 is withdrawn from the hinge knuckles.

In connection with the features above described, I have shown a suitable window operator 18 passing through a slotted plate 19 on the upright portion of the cage, said operator having notches 20 for engagement with an endwall of the slot, or with the screen wire covering 9, to hold the window 3 either in an open or a closed position. This operator 18 has its inner end connected to an 110 eye 21 secured to the window.

By providing the construction shown and

described or a substantial equivalent thereof, a window guard and ventilator is provided which will be simple and inexpensive, may be easily applied, and will be very desirable. As excellent results have been obtained from the details disclosed, these details are preferably followed, but within the scope of the invention as claimed, numerous minor changes may be made. It 10 will be understood that if the guard is applied to a window hinged at the bottom, the guard will be put in place in an inverted position so that the window can be swung open. The operator 18 would also be turned 15 so that it could properly engage the eye 21 secured to the window and latch plate of the guard.

I claim:

1. A window ventilator and guard comprising a cage adapted for application to the frame of a hinged window to guard the opening when the window is opened, said cage being open at one side to receive the window when the latter is opened, means for hinging said cage at one vertical edge to the window frame for movement away from the frame, means for detachably connecting

the opposite vertical edge of the cage to the frame, and means for hingedly connecting the window to the cage. 30

2. A device of the class described comprising a rectangular metal frame adapted to extend around the four sides of the frame of a hinged window, a plurality of substantially C-shaped metal bars secured at their 35 ends to two opposed bars of said rectangular frame, and a covering of woven wire extending over said C-shaped bars and secured to the four sides of said rectangular frame to form a cage having all sides of woven wire for guarding the opening when the window is swung into said cage. 40

3. A structure as specified in claim 2; together with means for hinging one end bar of said rectangular frame to the window 45 frame, a securing bar at the opposite end of the cage hooked at one end to take over one of said C-shaped bars and having a lateral foot at its other end, and means for detachably securing said foot to the window 50 frame.

In testimony whereof I have hereunto affixed my signature.

JACOB KILCHER.
